CLAIM

The ornamental design for a jockey box as shown and described.

DESCRIPTION

FIG. 1 is a front perspective exploded view a jockey box showing my new design;

FIG. 2 is a top perspective exploded view thereof;

FIG. 3 is a front perspective view thereof;

FIG. 4 is a front elevation view thereof;

FIG. 5 is a rear elevation view thereof;

FIG. 6 is a right side elevation view thereof;

FIG. 7 is a left side elevation view thereof;

FIG. 8 is a top plan view thereof;

FIG. 9 is a bottom plan view thereof; and,

FIG. 10 is a rear perspective view thereof.

The broken lines in the drawings depict portions of the jockey box that form no part of the claimed design.

1 Claim, 10 Drawing Sheets
